UNITED STATES PATENT OFFICE.

ARCHIE J. BROWN, OF CHICAGO, ILLINOIS.

ELECTRIC SIGN.

1,129,632.

Specification of Letters Patent. Patented Feb. 23, 1915.

Application filed April 20, 1914. Serial No. 838,146.

To all whom it may concern:

Be it known that I, ARCHIE J. BROWN, a citizen of the United States, and a resident of Chicago, in the county of Cook and State of Illinois, have invented an Improvement in Electric Signs, of which the following is a specification.

This invention relates to advertising devices, and more particularly to an illuminating display sign.

One of the principal objects of the invention is to provide a sign constructed so that the advertising matter will be clearly discernible in the daytime, and in the night-time by means of a source of light.

Another object of the invention is to provide a sign including a sign card or mask having the advertising matter cut therefrom, said mask being of a dark color and placed with relation to a white translucent glass, so that the latter may be viewed through the advertising matter to set out the letters and words forming the latter in the daytime, the letters being set out at night by means of a source of light placed beyond the translucent glass, the construction of the device being such that the masks containing the advertising matter may be exchanged when desired.

An additional object of the invention is to provide a device of the class described which will be simple, durable, efficient in operation, and inexpensive to manufacture.

With these and other objects in view which will become apparent as the description proceeds, the invention resides in the construction, combination and arrangement of parts hereinafter more fully described and claimed and illustrated in the accompanying drawing in which like characters of reference indicate like parts throughout the several figures, of which—

Figure 1, represents a front elevational view of the device, Fig. 2, represents a rear elevational view of the display frame, Fig. 3 represents an enlarged vertical transverse sectional view taken on the plane indicated by the line 3—3 of Fig. 1, looking in the direction indicated by the arrow, Fig. 4, represents a horizontal sectional view taken on the plane indicated by the line 4—4 of Fig. 3, Fig. 5, represents a side elevational view of the display frame showing the manner of placing the mask therein, and, Fig. 6, represents a fragmental perspective view of one corner of the translucent glass holder.

Fig. 7 represents an enlarged fragmentary sectional view indicating the manner of the disposition of the colored tissue.

Referring more particularly to the drawing, the device comprises what may be termed a display frame A detachably secured by means of hooks 5 to an illuminating or light holding box B. The latter is substantially rectangular in shape and is closed on all sides except one, upon which latter side the display frame is adapted to be secured when the device is in operative position. The light box is provided with four long, straight electric light globes 6, disposed one above the other in pairs in the rear corners of the box, and adapted to reflect light by means of angularly arranged mirrors 7 against and through a pane of translucent white glass 8 carried by an inner rectangular frame 9 disposed within rabbets cut in the inner edges of the display frame A, said inner frame at its rear edge lying flush with the rear edge of the display frame and in turn having its forward inner edges rabbeted to receive the translucent glass 8, the latter being maintained securely in place by means of a strip of metal or other suitable material 10, secured on the forward edges of the inner or glass holding frame.

The depth of frame 9 is somewhat less in depth than the rabbet provided in the frame A, and interposed between the bottom of last said rabbet and the frame 9, and supported by frame A, is a sheet of transparent glass 11. The inner frame 9 is hinged at its lower edge as at 12 to frame A, and may be secured in position therein by means of turn buttons 13 carried by the upper edge of the latter frame.

The letters forming the advertising matter, are stamped or cut from what may be termed a mask 14 which comprises a sheet of carboard or other suitable material whose front face is preferably of a dark color, or of some color strongly contrasting with white, and the mask is of a shape to fit within the binding strip 10, and against the translucent glass 8, and the mask is preferably of a thickness equal to the thickness of the binding strip, so that when in assembled position, as indicated in Figs. 3 and 4, the mask will be securely held in position between the transparent and translucent sheets of glass, and will be supported at its edges by means of the binding strip 10.

By the construction described, it is evident that by reason of the white translucent glass 8 being discernible through the letters 15 of the mask, the latter will be vividly disclosed in the daytime against the background of the remaining portion of the mask, and that at night upon the lighting of the lamps 6, a very effective and attractive illumination of the letters will be attained by reason of the light passing through translucent glass 8.

Although the best result may be attained by illuminating the sign by means of a box such as disclosed, it has been found that the 15 box may be dispensed with and that a very effective result will be attained by placing the sign in a brightly illuminated showcase or window. If so desired, tinted tissue or other thin paper 16 may be disposed between the mask and the translucent glass as indicated in Fig. 7. The frame A may be quickly removed at any time from the light box, and the inner frame opened so that the mask contained by the frame may 25 be exchanged for another.

The device is extremely simple in construction and yet effective and efficient in its operation, and may be assembled and taken apart in a very short time and with a 30 minimum of trouble, and may be readily transported from place to place.

Although I have described the preferred embodiment of my invention, I may desire to make such changes in the construction, 35 combination and arrangement of parts thereof as do not depart from the spirit of the invention and the scope of the appended claims.

I claim:

40 1. A device of the class described comprising an illuminating box, a display frame adapted to be detachably secured thereto, said frame having its inner edges rabbeted at the back, an inner frame adapted to be

disposed within the rabbet, said inner frame 45 being hinged to the display frame, said inner frame having its forward inner edges rabbeted, a sheet of translucent glass disposed within the rabbet in the frame, a binding strip secured to said inner frame 50 over the edges of said glass, a sheet of transparent glass disposed within the rabbet of the display frame, and a mask disposed between said panes of glass, said mask comprising a sheet of suitable material disposed 55 against the translucent glass and supported at its edges by the binding strip, said strip and mask being of substantially the same thickness.

2. A device of the class described, comprising a display frame, an inner frame hingedly connected therewith, a sheet of translucent glass supported by the inner frame, a sheet of transparent glass supported by the display frame, a binding strip 60 for securing said translucent glass to the inner frame, and a mask comprising a sheet of suitable material adapted to be disposed against said translucent pane and between the same and said transparent pane, said 65 mask being supported at its edges by said binding strip.

3. A device of the class described comprising a display frame, an inner frame associated therewith, a sheet of translucent 70 glass supported by the inner frame, a sheet of transparent glass supported by the display frame, a sheet of material having advertising matter in the form of characters 75 thereon and disposed between said panes 80 of glass and a binding strip carried by the inner frame between the glass panes and adapted to support said sheet of material in position.

ARCHIE J. BROWN.
